UNITED STATES PATENT OFFICE.

AIMÉ VUILLIER, OF BROOKLYN, NEW YORK.

ECCENTRIC.

SPECIFICATION forming part of Letters Patent No. 447,386, dated March 3, 1891.

Application filed November 29, 1890. Serial No. 373,056. (No model.)

To all whom it may concern:

Be it known that I, AIMÉ VUILLIER, of Brooklyn, in the county of Kings and State of New York, have invented certain new and useful 5 Improvements in Eccentrics; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in eccentrics in which the degree of eccentricity 15 can be enlarged or diminished at will. The object of my invention is to provide an eccentric in which the degree of eccentricity, and consequently the lateral motion imparted by the eccentric, can be increased or diminished 20 at will. I attain this object by the mechanism illustrated in the accompanying drawings, in which—

Figure 1 is a perspective view of the eccentric as it appears removed from the shaft. 25 Fig. 2 is a perspective view of the pin or lug of the eccentric, showing the same affixed to a rotating shaft. Fig. 3 is an end view of the eccentric on the shaft, showing the eccentric set at a point where the degree of eccentricity 30 is at the minimum. Fig. 4 is an end view of the eccentric on the shaft, showing the eccentric set to the maximum degree of eccentricity.

Similar letters refer to similar parts 35 throughout the several views.

The letter A represents a sleeve having an eccentrically-located bore; the letter B, an eccentric pin or lug extending from the shaft C of the eccentric. The letters E E represent 40 the sockets in the bore of eccentric sleeve A, and the letters f f the cogs in the eccentric pin or lug B. The sleeve A and lug B are provided with suitable means for holding the sleeve in the desired relative position on the lug, such as intermeshing cogs and sockets, 45 as hereinafter set forth.

The sockets E E and the cogs f f are so constructed as to fit securely into each other and hold the eccentric sleeve A firmly on the 50 eccentric pin or lug B, and are made so that

any of the cogs f f will fit into any of the sockets e e, so that the eccentric sleeve A may be adjusted at any position on the eccentric pin or lug B.

For the purpose of modifying the degree 55 of eccentricity the eccentric sleeve A can be placed on the eccentric pin or lug B in a position such as is shown in Fig. 3 of the accompanying drawings, when the degree of eccentricity is the least, or in the position 60 shown in Fig. 4, when the maximum degree of eccentricity is produced, or in any other position between these two positions and the degree of eccentricity, and consequently the lateral motion imparted by the eccentric can be 65 modified as desired. The number of the cogs f f and the sockets e e can be modified in constructing the eccentric sleeve and pin according to the number of adjustments which may be desired.

In the accompanying drawings the eccentric is represented as a circle; but an eccentric arm or any other shape may be adopted.

The eccentric pin or lug B in the accompanying drawings is located on the rotary 75 shaft C; but it may be located either on the shaft itself or at any point on a shaft, arm, or disk connected with the rotary shaft C.

Having thus fully described my invention, what I claim as new, and desire to secure by 80 Letters Patent, is—

1. The combination, with the rotary shaft having an eccentric pin or lug, of a sleeve provided with an eccentrically-located bore, said sleeve and pin or lug being provided 85 with corresponding cogs and sockets, substantially as described.

2. The combination, with a shaft having an eccentric lug or pin rotating with the shaft and provided with cogs and sockets, of a 90 sleeve having an eccentrically-located bore adapted to receive the eccentric lug, and being provided with cogs and sockets to engage the cogs and sockets of the lug, whereby the sleeve can be adjusted and its degree of eccentricity changed at will, substantially as 95 described.

3. The herein-described eccentric, consisting of the eccentric-pin carried by a shaft and the sleeve on said pin provided with an 100

eccentric bore, said sleeve being capable of adjustment on the pin to vary the degree of eccentricity, said pin and sleeve being provided with means, substantially as described, 5 for relatively holding or locking said parts together in the desired position against separate rotation, as set forth.

In testimony that I claim the foregoing as my own I affix my signature in presence of two witnesses.

AIMÉ VUILLIER.

Witnesses:

WM. G. A. PATTEE,
CHARLES W. JANES.
